Application November 23, 1937, Serial No. 176,068

4 Claims. (Cl. 235—100)

The present invention relates to a coin bank and has for an object to provide a self-contained compartment to receive and register coins.

Another object is to provide an improved bank 5 in which the coin receiving and registering mechanism is contained in the cover for a coin holding box.

Another object is to construct the mechanism so as to produce a registering device in a compartment of minimum depth.

A further object is to provide new means for compensating for coins of various sizes and denominations.

With the foregoing and other objects in view, 15 the invention will be more fully described hereinafter, and will be more particularly pointed out in the claims appended hereto.

In the drawings, wherein like symbols refer to like or corresponding parts throughout the several 20 views.

Figure 1 is a perspective view of a coin bank with parts broken away.

Figure 2 is an end view of the coin bank.

Figure 3 is a top plan view of the coin bank with 25 the upper wall of the cover and certain of the uppermost parts removed.

Figure 4 is a vertical section taken on the line 4—4 of Figure 3.

Figure 5 is a vertical section taken on the line 30 5—5 of Figure 3.

Figure 6 is a vertical section taken on the line 6—6 of Figure 3.

Figure 7 is a vertical section taken on the line 7—7 of Figure 3.

Figure 8 is a fragmentary top plan view of the 35 registering mechanism lying just beneath the top wall of the cover.

Figure 9 is a top plan view of the cover mechanism with parts removed.

Figure 10 is a fragmentary top plan view of the 40 penny registering mechanism.

Figure 11 is an enlarged detail of the slot forming member.

Figure 12 is an enlarged detail of the slide em- 45 ployed in the penny registering mechanism.

Figure 13 is a detail view of the compensating lever used in the nickels, dimes and quarters registering mechanism, and

Figure 14 is a detail enlarged view of the key 50 used in locking the registering cover on the box.

Referring more particularly to the drawings, Figures 1 and 2 show a box 19 of any suitable size and construction to receive the coins. The box 19 is open at its top and a registering cover structure 20 is placed thereover. The cover is com-

posed, as more particularly shown in Figure 4, of a lower pan shaped part 20^b and an upper part 20^a which fits down over the pan shaped part. The two parts of the casing are adapted to be secured together in any suitable way, such as by spot welding at 89. The part 20^b of the casing carries at one end a pair of laterally spaced lugs 22 and the box 19 has, at one of its end walls a pair of corresponding slots 21. The opposite end wall of the box 19 is provided with a slot 23 which is designed 10 to receive a key 62 to hold the cover releasably on the box. The cover 20 is a self-contained compartment of relatively shallow depth, such a structure being made possible by the particular registering mechanism hereinafter described.

The top 20^a has near one edge three parallel coin receiving slots 25 for the pennies, 26 for the nickels and quarters, and 27 for the dimes. The upper side of the part 20^a is marked opposite the respective slots with the designation of the coins for 20 which the slots are adapted.

Referring now particularly to the penny registering mechanism, Figure 7 shows that the slot 25 is preferably formed by bending down the metal of the upper part 20^a so as to leave a downturned 25 metal tongue 25^a at one end of the slot 25. Between the parts 20^a and 20^b of the cover is freely positioned the slide 33, shown in detail in Figure 12. One end of the slide 33 is bevelled as at 34 and adapted to receive the edge of a penny there- 30 against. The direction of the bevel or inclination 34 enables various sizes of pennies to have their peripheral edges seat against some part of the bevel 34. The other edge of slot 25 is fixed. The underside of the slide 33 is cut-away at 33^a. A portion of the bottom portion 20^b is pressed up at 40 to form an upstanding lug which fits into the cut-away 33^a of the slide 33. The lug 40 therefore limits the extent of movement of the slide 33. The end of the slide 33 opposite the 40 bevelled shoulder 34 is cut away to provide a depression 36^a, an upstanding tooth 35 and a flat end portion 36. A ten-toothed wheel 37 is mounted on a shaft 38 which is journaled in the lower member 20^b of the cover. The wheel 37 is 45 located so that its teeth are in the path of travel of the slide 33, as shown in Figures 3, 7 and 10. A spring 41 presses on the end of the slide 33 and biases it to the zero position shown in Figure 7. A second spring 39 presses against the side of 50 the slide 33 and yieldably holds it in the path of the teeth of the wheel 37.

When a penny is inserted into the slot 25 one edge strikes the fixed tongue 25^a so that the thrust of the penny is directed in the opposite direction 55

against the shoulder 34 of the slide 33. When the penny is pressed through the slot the slide 33 is displaced longitudinally and the tooth 35 of the slide 33 engages one of the teeth of the wheel 37 and advances the wheel. As the wheel 37 rotates, counter-clockwise, as shown in Fig. 3, one of its teeth will slide into the depression 36^a and a succeeding tooth will strike against the side of the slide 33 displacing the slide laterally against the force of the spring 39. When the slide has been displaced sufficiently to clear the tooth 35 of the teeth of the wheel 37 the spring 41 will return the slide to its zero position. The extent of travel of the slide and the relation with the wheel 37 are such that the wheel 37 is moved only one tooth when a penny is inserted in the slot 25.

With reference now to the mechanism for registering the other coins, the slots 26 and 27 are preferably formed by pressing down a portion of the material of the upper part 20^b of the cover. Here, however, the downwardly directed tongues 25^b and 25^c are located at the opposite end of the slots. The vertical partitions between the slots are formed by means of a member 81, shown in detail in Figure 11. The lower portion 20^b of the cover is cut away as at 80 in Figure 9. The cut is made to provide small extensions 83 at one end and extensions 83^a at the opposite end. An upstanding wall 88 is also pressed out of the bottom portion. The slot forming member 81 is composed of two spaced side walls connected at one end by a web. The end carrying the web is cut away to give a pair of downwardly extending legs 82 which are designed to fit into the extensions 83^a of the cut away portion 80. The opposite end of the member 81 is cut down to give a pair of horizontal portions 85 which fit into the extensions 83 of the cut away portion 80. At its outermost end the member 81 has the side walls bend down to form flat lugs 84 which are designed for attachment to the underside of the bottom portion 20^b. The penny slot 25 is defined by the side wall of the lower portion 20^b of the cover and one wall of the member 81. The nickels and quarters slot is defined by the two walls of the member 81. The dimes slot is bounded by the inner wall of the member 81 and the pressed up wall 88.

Along the edges of the slots 26 and 27 opposite the tongues 25^b and 25^c is placed a lever 28 which is pivoted at 30 on a pin journalled in the bottom portion 20^b of the cover. The lever 28 is biased to lie against the ends of the slots 26 and 27 by means of a spring 60 shown particularly in Figure 13. At the end of the lever 28 opposite its pivot 30 is a loop spring 45 which is coiled around a pin 28^a and has its arm 45^a resting against the inner side of the lever 28 which is channel shaped. A toothed wheel 44 provided with forty teeth is mounted on a shaft 44^a which is journalled in the lower portion 20^b of the cover. The outer end of the loop spring 45 engages with the teeth of the wheel 44 so that when the lever 28 is swung in the direction of the arrow in Figure 3 the wheel 44 will be rotated in a clockwise direction.

When a nickel is inserted in the slot 26, as seen in Figure 6, the lever 28 will be moved to a slight extent. This motion is magnified by leverage and the loop spring 45 pulls the wheel 44 one tooth. When a quarter is inserted in the same slot 26, the greater diameter of this coin produces five times the movement of the lever 28 and the loop spring 45. The wheel 44 is thereupon moved by five teeth.

With reference to Figure 5, it will be seen that

the lever 28 extends a substantial distance across the slot 27 so that it is displaced diagonally upon the insertion of a dime. The position of the lever 28 is such that the insertion of a dime through the slot 27 produces a swing of the lever which causes the loop spring 45 to pull the wheel 44 two teeth.

It will be understood that the positioning and proportioning of the lever 28 is purely a matter of design to be worked out for the particular size given to the mechanism. The guide or standard according to which the construction is to be made is that the insertion of a nickel must produce a throw of the lever 28 sufficient to move the wheel 44 by one tooth whereas the insertion of a quarter in the same slot must produce five times that throw. The insertion of a dime in the slot 27 must produce double the throw of the lever 28 as the nickel in the slot 26 produces.

The above structure is that which is primarily designed to be moved by the insertion of the coins. In order to have a complete register it is necessary to interrelate the above mechanism and add thereto a totalling device.

The wheel 37, as above described, has ten teeth each corresponding to one penny. The wheel 44 has forty teeth each corresponding to a nickel. Fixed to the pin or shaft 38 so as to revolve with the wheel 37 is a plate 43 which has at diametrically opposed positions two teeth. These teeth are aligned with two of the teeth of the wheel 37 and are placed at a plane which will bring them into contact with the teeth of the wheel 44 so that every half revolution of the wheel 37 will produce a rotation of the wheel 44 by an amount equal to one tooth of the wheel 44. As seen in Figure 5, the wheel 44 is in a plane elevated above that of the wheel 37 and the plate 43 is placed in the plane of the wheel 44.

A wheel 50, which here has twenty teeth, is mounted on a pivot 50^a which is journalled in the bottom portion 20^b of the cover. The teeth of the wheel 50 are located to mesh with the projections 47 and 48 of a plate 46 which is fixed to the wheel 44. These projections 47 and 48 extend at diametrically opposite positions beyond the edges of the teeth of the wheel 44. At every half revolution of the wheel 44 the wheel 50 will be advanced one tooth by contact with one of the projections of the plate 46. The teeth of the wheel 50 therefore correspond each to one dollar. At one point 57 on the wheel 50 the space between the teeth is made greater. A locking lever 24, pivoted at 30, has a nose 58 which will fit in the enlarged space 57 between the teeth of the wheel 50 but will not fit between any other pair of the teeth. This locking lever 24 is pressed by the spring 60 acting on the lug 59 struck up on the lever to keep the key 62 extended through the slot 61 in the edge of the bottom portion 20^b of the cover. This key 62 is adapted to extend through the slot 23 in the box 19 to hold the cover structure 20 on the box. When the wheel 50 is rotated sufficiently to place the space 57 opposite the nose 58 of the locking lever 24 the key 62 may be pressed in by hand and the cover 20 removed from the box 19 to give free access to the coins. In the form of device here shown the space 57 will come opposite the nose 58 only after twenty dollars worth of coins have been placed in the box.

In order to make the registering mechanism accurate various spring stops are employed to limit the rotation of the wheels. Thus, a spring 42 bears against the edge of the penny wheel 37 to limit its rotation to one tooth in clockwise direction and to prevent the wheel 37 from moving

in a counter-clockwise direction. The spring 42 is really an arm of the same spring of which the spring 39 is another arm. A clip 42^a serves to hold the two armed spring to the edge of the casing. 5 The pressure of the spring 42 upon the teeth of wheel 37 is such, and the curved portion of the spring 42 is such, that as the wheel 37 is being moved by the action of a penny upon 33, this certain amount of spring pressure of the spring must 10 be overcome.

The wheel 37, having been moved a tooth, it is held by such spring pressure in ready position for the next penny, and due to the curvature of the spring 42, its end abuts against the rear side of 15 a tooth and thereby prevents the wheel from moving clockwise.

A toothed wheel 56 is mounted on the pin 44^a. The wheel 56 and the plate 46 are secured to the wheel 44 by means of a pair of pins 65^a which extend through the three, as seen in Figure 4. An arm 55 of a spring bears against the teeth of the wheel 56 to retard forward motion of the wheel 44. The arm 55 is shown as a part of the spring which includes the arm 41 that bears on the end 25 of the slide 33. The spring including these two arms is held by the clip 41^a.

A spring 54 presses against the teeth of the wheel 44 to prevent counter-clockwise rotation thereof. The spring arm 54 is held in a clip 53 along with the springs 51 and 52 which bear on 30 the teeth of the wheel 50. The spring 51 prevents backward rotation of the dollar wheel while the spring 52 retards forward rotation.

As shown in Figures 4 and 8, the wheel 44 may 35 be drivingly connected to an indicating disc 65 which has numerals on its face corresponding in five cent intervals to the teeth of the wheel 44. If the wheel 44 has forty teeth the disc 65 counts to a dollar by five cent intervals twice for each 40 revolution. An indicator wheel 64 may likewise be secured to rotate with the dollar wheel 50 and the face of the wheel 64 will be calibrated up to twenty dollars. The upper portion 29^a of the cover will have openings or windows 66 through 45 which the indicated total may be viewed. This total will show when twenty dollars are accumulated so that the key 62 can be depressed and the bank opened.

The pins 38, 44^a and 50^a may either be journaled in the bottom of the cover or they may be fixed thereto and surrounded by bushings. The spring clips 41^a, 42^a and 53 may readily be pressed out of the walls of the lower portion 29^b if the same is made of sheet metal. The whole construction is very readily and cheaply made of sheet metal and most of the parts readily lend themselves to formation by a stamping operation.

The device is simplified by having only two mechanisms responsive to coins. The one is responsive only to pennies and the other is adapted to compensate in its response to nickels, quarters and dimes. Both provide for coins of the same value but with different diameters due to peripheral wear. This differential mechanism, therefore, takes the place of three separate coin responsive devices. The coin responsive mechanisms are simply correlated and totalled.

Of course, it is obvious that the numbers of teeth in the wheels is by no means critical and the 70 device may readily be adapted to coins of any value whatever, excepting that the wheel 44 is shown with forty teeth, which is a multiple of twenty. Twenty teeth or a multiple thereof is a critical number. Likewise, the locking device may 75 be made to function at any desired total.

For the proper functioning of the device, it is imperative that the teeth of the gear on being moved by the different coins, come to a definite stop against pawl springs, namely, 42, 54, and 51.

However, due to the differences of the new and 5 old coin diameters and coin thicknesses, an "over-run" takes place, which must be counteracted by means of a return spring 41 and overthrow pawl springs 55, and 52.

The gears, by being kept at all times in their 10 respective exact final position, notwithstanding their varying forward movements, will allow for proper mesh with the corresponding transfer teeth and key or lock lever.

The box unlocking member 24 can be provided 15 with a spring to press the head 58 against the peripheral portions of the teeth 49, by a gentle pressure so as not to impede the rotation of the wheel 50, and when the head 58 registers with the opening or space 57, the pancake compartment 20 will become unlocked automatically from the receptacle.

It is obvious that various changes and modifications may be made in the details of construction and design of the above specifically described 25 embodiment of this invention without departing from the spirit thereof, such changes and modifications being restricted only by the scope of the following claims.

What is claimed is:

1. A coin bank comprising a coin holding body, a coin receiving cover for said body having spaced top and bottom plates with a connecting web around their edges, said top plate having three parallel coin slots near one edge and parallel 35 thereto, said bottom plate having an opening corresponding to the three slots and further having an upstanding portion forming a wall for the innermost slot, a channel member with spaced side walls open top and bottom beneath the 40 middle slot to form walls for said slot and simultaneously to form a second wall for the innermost slot and one wall for the outermost slot, the other wall of the outermost slot being the connecting 45 web between the plates.

2. A coin bank comprising a registering compartment having a coin slot therein, a slide bar located in said compartment to slide partly across the coin slot and adapted for longitudinal displacement by the edge of a coin inserted into said 50 slot, a fixed guide along one side of said slide, a guide spring pressing on the opposite side of said slide to hold it yieldably against said fixed guide, and a toothed registering wheel rotatably mounted in said compartment and adapted to be 55 rotated by said slide when the same is displaced, rotation of said wheel by said slide causing a tooth of the wheel to displace the slide radially against the guide spring to disengage the slide from the wheel after a predetermined rotation. 60

3. A coin registering mechanism for coin banks, comprising a compartment formed of two spaced parallel walls and having enclosing side walls, coin passage slots in the spaced parallel walls, coin guide walls disposed in the compartment between the spaced walls having openings in registration with the slots of the spaced walls, each having an open end, one of said guide walls being for dimes, and one for nickels and quarters, a spring held lever arranged to close the open ends 70 of said guide slots, a pivot connection between the said lever and one of the walls of the compartment, the pivot connection being arranged at one side of the nickel-quarter guide slot and distant from the dime guide slot, and the free 75

end of the lever extending beyond the dime guiding means, the lever being normally in an inclined position in respect to the axes of the guide slots, presenting an edge contact to the edges of the coins when inserted into the guide slots, a toothed wheel disposed in the compartment between the spaced walls, having teeth each indicative of five cents, means for rotatably holding the toothed wheel in a position near the coin guide slots, and means connecting the free end of the lever with the wheel teeth, whereby insertions of dimes move the lever a distance to move the toothed wheel two teeth, the insertion of a nickel moves the lever a distance to move the toothed wheel one tooth, and the insertion of a quarter moves the lever to move the toothed wheel five teeth.

4. In a coin bank, a coin registering mechanism comprising in combination a compartment to receive the mechanism, a plurality of coin slots in the top of said compartment, one of said slots adapted to receive both nickels and quarters,

guide walls between said slots within the compartment, said coin slots being closed at one end and open at the other, a spring lever inclined to the slots and positioned to close the open ends thereof, registering means in said compartment including a toothed wheel and a numbered disc, a shaft journaled in the top and bottom of the compartment and receiving said wheel and the disc, connecting means between the spring lever and the wheel whereby the wheel and disc are actuated by the spring lever when the same is displaced by the insertion of a dime, a nickel or a quarter, separate registering means for pennies including a, 5 10 15 20 25 30 35 40 45 50 55 60 65 70 75 80 85 90 95 100 105 110 115 120 125 130 135 140 145 150 155 160 165 170 175 180 185 190 195 200 205 210
